EDWIN S. PEARCE AND EDMOND C. KARIBO, OF INDIANAPOLIS, INDIANA

PRESSURE IMPULSE DAMPENER

Original application filed October 21, 1925, Serial No. 63,827. Divided and this application filed October 26, 1929. Serial No. 402,556.

This invention relates to pressure impulse dampeners, and involves a construction which is particularly useful in association with fluid-pressure-actuated devices, where the pressure of the fluid is pulsating or irregular, while the device acted upon by the fluid should operate without violent momentary fluctuations.

An example of such use of the present invention is well illustrated by our co-pending application, Serial No. 63,827, filed October 21, 1925, issued as Patent No. 1,737,199, November 26th, 1929, for indicating apparatus for locomotive back pressure (of which the present application is a division). In that application there is illustrated an indicator, actuated by the exhaust pressure of a steam locomotive to give continuous direct indication to the engineman as to how he should operate the reverse lever of the locomotive to maintain the optimum mean back pressure. The pulsating exhaust, before passing to the indicator, is passed through the pressure impulse dampener, or choke, embodying our present invention, to effect a smoothing or "ironing out" of the severe exhaust impulses of the locomotive.

This invention therefore involves, primarily, the damping of pressure impulses in a fluid-pressure line, especially in order to deliver to a device to be operated by the fluid a more uniform pressure so as to effect smooth operation of the device and to protect it from excessive fluctuations or vibrations.

More specifically, the invention involves the attainment of the foregoing by an effective, simple and inexpensive device; which is compact so as to fit into a small space; and easy to assemble, install, inspect, clean and repair; and which can be readily accommodated to any particular pipe-line arrangement in which it is to be used, and this without necessitating additional couplings, elbows or other pipe joints.

The invention still further involves the provision of such a device which is as rugged as it is simple, in which certain elements may be made counterpart and interchangeable, and which by its general arrangement

naturally permits a drainage of condensate therethrough.

How these objects and advantages are attained, together with others which are incident to the invention or which will occur to those skilled in the art, will be evident from the following description taken together with the accompanying drawing, in which drawing:

Fig. 1 is a somewhat diagrammatic side co-elevational view of a locomotive illustrating one application of our invention;

Fig. 2 is a detailed view, partly in side elevation and partly in longitudinal section, of the damping device embodying our invention; and

Fig. 3 is a transverse section of the device, taken on the line 3-3 of Fig. 2.

Referring first to Fig. 1, it will be seen that we have illustrated a locomotive 2, from the exhaust cavities 3, of which suitable piping 4, 4 conveys exhaust steam to a common pipe 5. The pipe 5, extending back to the indicator or other pressure-operated device 6 in the cab 7, may conveniently be placed beneath the sheathing or lag-covering 8 of the locomotive boiler, as shown, to minimize pressure variations from changes in temperature and to preserve a neat appearance.

Our pressure impulse dampener, indicated generally, in Fig. 1, by reference numeral 9, being small and compact, may be placed at any convenient point in the line 5 and lends itself readily to location under the sheathing 8 if desired. As will further appear herein-after, from the detailed description of the device, its construction also makes possible its convenient connection into the pipe-line 5, or any other point of use, without necessitating additional bends, elbows or fittings in the pipe in which it is inserted.

By reference now to Figs. 2 and 3, it will appear that the damping device is of a very simple and rugged construction, easy to assemble and to take apart for cleaning, and constructed of a minimum number of parts. The casing or wall 10 is equipped at each end with a cap piece 11, and centered by these caps, within the chamber 12 thus formed, is a baffle or screen 13 having a ring

14 within it through which the bolt 15 passes, this bolt being extended through both caps and clamping the whole structure firmly together by means of the nut 16. The two caps 11 are identical, each having a lateral extension or pipe connection 17 which is formed with a restricted passage or nozzle 18 toward the inside. A valuable feature of the dampener, bearing on the ease of assembly and 10 actual installation of the device, is the construction of the cap-pieces, which may be turned through any degree relatively to each other or to the cylindrical shell (as seen in dot-and-dash lines at 17a in Fig. 3) while at 15 the same time the planes of the inlet and outlet ports remain parallel, thus obviating the necessity for elbows and other fittings in the connecting piping, as is evident from Figs. 1 and 2.

20 The positioning of the screen 13, between the counterpart cap-pieces 11, is positive both as to endwise and lateral location, since the ends thereof seat within the sockets or recesses 18'. Furthermore, the mid-portion of 25 the screen is additionally supported by the annulus 14, which is centrally apertured to fit the bolt 15, and peripherally grooved to fit the constriction or internal shoulder 19 of the screen. The annulus, as will now appear, further serves the purpose of a baffle to direct the flow of pressure fluid.

In the application of the invention in the way illustrated in the drawing (and with particular reference to Fig. 2) the pulsating 25 fluid is admitted to the dampener through the lower connection 17 and its port 18, which decreases in diameter inwardly and initially tends to smooth out the impulses, and thence into the space 13a, on one side of ring 14, inside the screen or foraminous members 13. Passing outwardly through the openings of 40 the screen, it then flows upwardly through the annular chamber 12, back through the screen 13, on the other side of ring 14, into chamber or space 13b, and then out through 45 the upper port 18, which, widening outwardly, acts to reduce the velocity of the now smoothed-out pressure stream as it leaves the device.

50 We have found that the baffle and screen arrangement, in conjunction with, and positioned between, ports which are oppositely tapered with respect to the direction of flow, provides very effective damping as compared 55 with devices heretofore used. The construction of the device as an elongated chamber, with inlet and outlet connections extending laterally at each end thereof, permits the simplest possible mounting of the device, in a 60 vertical position, between two sections of substantially horizontal (or slightly sloping) pipe, such as in the assembly of Fig. 1, which provides for automatic natural drainage of condensate down into the lower pipe section.

65 The securing of the parts by a single cen-

trally-disposed retaining means or bolt insures an even pressure on the circumferential juncture of shell 10 and caps 11 to keep the joints tight; permits the opening of the housing for inspection, repair, or cleaning out of carbon deposits, without the necessity of disconnecting the pipe connections; and permits of angularly disposing the pipe sections with respect to one another at any angle in the 70 360° around the circumference of the barrel, 75 according as the installation may require.

What we claim is:—

1. A fluid-pressure-pulsation dampener comprising a casing; a tubular screen positioned within and longitudinally of said casing; an inwardly extending annular member in said screen; a removable cap at each end of the casing having a central aperture, a laterally extending tapered port and a shoulder abutting against said screen; and a retaining member extending through said cap apertures and said annular member. 80

2. A fluid-pressure-pulsation dampener comprising a casing; a tubular screen positioned within and longitudinally of said casing; baffle means in said casing cooperating with said screen intermediate the ends of the latter to support the same and guide the fluid; a removable cap at each end of the casing having a center aperture, a laterally extending tapered port and a shoulder abutting against said screen; and a retaining member extending through said cap apertures and said baffle means. 90

3. A fluid-pressure-pulsation dampener comprising a tubular casing, baffle means therein, counterpart inlet and outlet heads at the ends of said casing provided with inlet and outlet connections disposed in substantially parallel planes transverse said casing and radially of the longitudinal axis of the latter, said baffle means being positioned by said casing and by said heads, and means of relative angular abutment between the radially extending connections of said heads, 100 said adjustment means including a rotational adjustment for at least one of said heads and a releasable through bolt extending centrally through said heads and longitudinally of the 105 said tubular casing. 110

In testimony whereof we have hereunto signed our names.

EDWIN S. PEARCE.

CERTIFICATE OF CORRECTION.

Patent No. 1,891,008.

December 13, 1932.

EDWIN S. PEARCE ET AL.

It is hereby certified that error appears in the printed specification of the above numbered patent requiring correction as follows: Page 2, line 40, for "members" read "member"; and line 109, claim 3, for "abutment" read "adjustment"; and that the said Letters Patent should be read with these corrections therein that the same may conform to the record of the case in the Patent Office.

Signed and sealed this 24th day of January, A. D. 1933.

(Seal)

M. J. Moore,
Acting Commissioner of Patents.
